(57) **CLAIM**

The ornamental design for a security tag, as shown and described.

DESCRIPTION

FIG. 1 is a perspective view of first embodiment of a security tag showing our new design;

FIG. 2 is a reverse perspective view thereof;

FIG. 3 is a top view thereof;

FIG. 4 is a bottom view thereof;

FIG. 5 is a right view thereof;

FIG. 6 is a left view thereof;

FIG. 7 is a front view thereof;

FIG. 8 is a rear view thereof;

FIG. 9 is a perspective view of a second embodiment of a security tag;

FIG. 10 is a reverse perspective view thereof;

FIG. 11 is a top view thereof;

FIG. 12 is a bottom view thereof;

FIG. 13 is a right view thereof;

FIG. 14 is a left view thereof;

FIG. 15 is a front view thereof; and,

FIG. 16 is a rear view thereof.

The dotted lines of equal length illustrate the environment and form no part of the claimed design.
